UNITED STATES PATENT OFFICE.

OSCAR P. NYSTROM, OF HOLLAND, MICHIGAN, ASSIGNOR TO HOLLAND FURNACE COMPANY, OF HOLLAND, MICHIGAN, A CORPORATION OF MICHIGAN.

SHEET-METAL-WORKING MACHINE.

1,332,354.

Specification of Letters Patent.

Patented Mar. 2, 1920.

Application filed May 20, 1918. Serial No. 235,613.

To all whom it may concern:

Be it known that I, OSCAR P. NYSTROM, a citizen of the United States of America, residing at Holland, in the county of Ottawa and State of Michigan, have invented certain new and useful Improvements in Sheet-Metal-Working Machines; and I do hereby declare the following to be a full, clear, and exact description of the invention, such as will enable others skilled in the art to which it appertains to make and use the same.

This invention relates to a machine for working and forming sheet metal, particularly various sections of metal which go to make up an elbow or a similar construction in smoke pipes of furnaces or other heating constructions, the invention being also adapted for making elbows in various types of pipes other than that mentioned, particularly the hot air pipes leading from a furnace to various rooms in a building heated by the same. It is a primary object and purpose of the present invention to provide a machine with which various continuous grooves and ridges may be formed at the ends of sections so that the same may be fitted and secured together to form an elbow, the invention consisting in many novel features of construction and arrangement of parts for effectively accomplishing the end desired.

For an understanding of the invention and the mechanism embodying the same, reference may be had to the accompanying drawings, in which,

Figure 1 is a side elevation, partly in section, of a sheet metal working machine embodying my invention.

Fig. 2 is a plan view of the rotary die-carrying member.

Fig. 3 is a vertical section therethrough and adjacent parts of a relatively stationary die member and support coöperating with the dies carried by the rotary member.

Fig. 4 is a side elevation of the construction shown in Fig. 2.

Fig. 5 is a fragmentary section, similar to that shown in Fig. 3, and illustrating a slight modification in the dies.

Fig. 6 is a horizontal section taken substantially on the line 6—6 of Fig. 1.

Fig. 7 is a side elevation, partly in section, of an elbow the sections of which are formed on the machine.

Fig. 8 is a plan view of the frame of the machine, the rotary die member being removed.

Fig. 9 is a vertical section substantially on the line 9—9 of Fig. 8.

Fig. 10 is a front view of the upper portion of the frame of the machine, and

Fig. 11 is a fragmentary side elevation, partly in section, of the mechanism for bringing the various dies together in operative position during the operation of the machine.

Like reference characters refer to like parts in the different views of the drawings.

In construction a relatively stationary table 1 is supported by a plurality of vertical supports 2, preferably, of tubular form, the same being connected and braced between their upper and lower ends by a cross member 3. The table 1 has a central opening through which a boss 4 projects in and through which a vertical shaft 5 is mounted, being slidable vertically through the boss but keyed thereto so that the boss rotates with the shaft. The lower end of the shaft extends a short distance below the member 3 and has pivotal connection to a lever 6 which is pivotally mounted at 3° to and below the member 3. Its front end extends in front of the forward supports 2 and is formed with a foot-engaging portion 7, while its rear end carries a weight 8, the normal tendency of which is to elevate the shaft 5 to upper position. The shaft extends through a vertical spacing member 9 connected to and extending above the member 3, above which a pulley 10 is connected with the shaft 5, the same being adapted to be driven by an endless belt 11 passing over any suitable driving pulley 12 on a drive shaft 13. The belt is guided around idle guide pulleys 14 which are mounted on suitable brackets 15 connected to the rear vertical supports 2, it being evident that the shaft 5 rotates continuously whenever the drive shaft 13 is in operation, the connection of the lower end of the shaft 5 to the lever 6 being one suitable to permit such rotation, as shown in Fig. 1.

Above the table 1 at the rear portion thereof a die member 16 is fixed, covering substantially the rear half of the table 1, in front of which at each side edge of the table 1 guides 17 are located between which a

movable die member 18 is slidably mounted. Coil springs 19 are interposed between the members 16 and 18, the tendency of which is to force the member 18 toward the front and away from the rear member 16. A head 20 having an inclined rear face 21 passes through an opening in the member 18, having a coöperating inclined face as shown in Fig. 9, the lower end of the head being connected to the upper end of a rod 22 which at its lower end has pivotal connection to a lever 23 pivotally mounted between its ends on the member 3 as shown in Fig. 11. A link 24 pivotally connects at its upper end to the rear end of lever 23, and at its lower end to the upper end of a second lever 25, also pivotally mounted at a point between its ends on the member 3, while a second link 26 connects the rear end of the lever 25 with the foot-operated lever 6. It is evident that upon depression of the front end of the lever 6 by the foot of the operator of the machine, the die member 18 is moved to the rear against the resistance of springs 19 bringing the adjacent edges of the members 16 and 18 together. As soon as the pressure of the foot upon the front end of lever 6 is removed, springs 19 move the member 18 to its normal position, the head 20 being elevated not only by the action of the weight 8, but also by a coil spring 27 disposed under the front end of the lever 23. This coil spring 27, however, is not absolutely essential and may be eliminated if desired.

A circular recess 28 is cut in the upper side of the table 1 and the members 16 and 18 around this recess are cut away in semicircular form as shown. In the edges of the semicircular portions of the members 16 and 18 dies are cut in the form of upper and lower grooves 29 as shown in Fig. 3. There may be one or more of these grooves, and in Fig. 5 I have shown a modification in which only one groove 29^a is formed in the member 18^a, similar to member 18, and of course the coöperating member 16 would likewise have one groove only.

A circular die-carrying member 30 seats in the recess 28 and is connected to the boss 4 to rotate therewith. In diametrically opposed sides thereof recesses are cut, over which retaining plates 31, one at each side of each recess, are secured to hold a sliding construction underneath, such construction comprising upper and lower connected plates 32 and 33 between which at their outer ends circular dies 34 are rotatably mounted, the same being formed with ridges to coöperate with the grooves 29 in the die members 16 and 18. In the modification shown in Fig. 5 the die 34^a has one ridge only to coöperate with the single groove 29^a.

A rod 35 is attached to each of the sliding constructions, extending inwardly therefrom and terminating in a head 36. A coil

spring 37 surrounds each rod 35 and is under compression, the tendency thereof being to draw the dies 34 away from the members 16 and 18 and force the heads 36 into grooves 38 cut in opposed sides of the shaft 5. It is evident, however, that on downward operation of the foot lever 6 and the consequent movement of the shaft 5 in a downward direction, the upwardly and outwardly inclined sides of the grooves 38 serve to force heads 36 and attached rods 35 in an outward direction, thereby carrying the dies 34 outwardly and into coöperation with the grooves 29. The downward movement of the shaft 5 is limited by a collar 39 secured at the upper end of the shaft as shown.

In operation a section, such as 40, of plain sheet metal, for a pipe elbow is placed at one end between dies 34^a and the coöperating groove members 16 and 18^a, after which a depression of the foot lever 6 is made forcing the dies 34^a against the metal and causing it to enter the grooves 29^a, this making a single bead on the sections 40 as indicated at 40^a. Other sections such as 41 that indicated at 41 are disposed in a similar mechanism between the dies 34 and the coöperating groove members 16 and 18 whereby, on depression of the foot lever, a double bead indicated at 41^a is made. The beaded ends of the sections 40 and 41 may then be fitted together and by another operation, which forms no part of the present invention, firmly secured together. It will be noted that on depression of the foot lever, the member 18 is moved over toward the part 16 and with the rotation of the die-carrying member 30, a smooth and continuous bead or double bead may be made on the section 40 or 41, and that as soon as the foot lever 6 is released and member 18 permitted to take its normal position, the beaded section is free to be taken from the mechanism. In fact, with thin sheet metal there is no necessity to use a movable member 18, but the grooves 29 or 29^a may be cut in a solid member which may be made by connecting the parts 16 and 18 together. But with heavier metals for heavier pipes, the movable die member 18 is advisable if not absolutely essential. Each section 40 or 41 is inserted between the die-carrying member and the grooved die members 16 and 18 and is left in momentarily while the foot lever is depressed, the beads in the metal sections being formed very rapidly, after which it is removed, permitting another section to be acted upon.

The construction described is very efficient for properly forming sheet metal sections, which may later be connected together to make pipe elbows for furnace or smoke pipes, and with which, production may be very greatly facilitated. In practical operation the mechanism has proven com-

pletely satisfactory. The mechanism is relatively simple but is very efficient for attainment of the desired ends.

I claim:

- 5 1. In combination, a support, a die member mounted on and above the support and provided with a circular opening in the sides of which a grooved die is formed, a rotary die member located in the opening in said
- 10 10 first die member, a rotating die mounted to move radially on said rotary die member, a vertical shaft on which the rotary die member is splined, said shaft having a groove formed with an upwardly and outwardly inclined side, a headed pin connected with the radially movable die, said head entering the groove in the shaft, means to normally hold said head in the groove, means to drive the shaft, and means to depress the
- 15 20 shaft thereby forcing the radially movable die outwardly to coöperate with the first mentioned die, substantially as described.
- 20 2. In combination, a supporting frame, a vertically positioned shaft rotatably mounted on the frame, a lever pivotally mounted on the lower portion of the frame to which the lower end of the shaft is connected, means tending to elevate the front end of the lever and to thereby raise the
- 25 30 shaft to upper position, a circular die carrying member splined on the shaft, a roller die movably mounted on said member for radial movements, means whereby on down-

ward movement to the front end of the lever and consequent downward movement of the 35 shaft, the roller die is moved outwardly, a coöoperating die member surrounding the circular die carrying member and formed with a die to coöperate with the roller die when it is projected outwardly, and means 40 to drive the shaft, substantially as described.

3. In combination, a circular member, a slide positioned radially thereon, a roller die mounted at the end of the slide, means normally moving the slide and die inwardly, 45 means to rotate said member, a second stationary member partially surrounding the circular member and provided with a co-operating die at its edge adjacent the circular member, a third member mounted to 50 move toward or away from the other members, said third member completing the surrounding of the circular member and also having a co-operating die formed at its adjacent edge, springs normally moving the third 55 member away from the other members, a foot operated lever, means disposed between the lever and the third member for moving said third member toward the other members on operation of the lever, and means 60 disposed between said lever and the slide to project the slide and roller die outwardly on operation of the lever, substantially as described.

In testimony whereof I affix my signature. 65
OSCAR P. NYSTROM.
